Primary Examiner — Cynthia Ramirez*Assistant Examiner* — Xavier Marti-Santos(74) Attorney, Agent, or Firm — Cramer Patent & Design, PLLC; Aaron R. Cramer(57) CLAIM

The ornamental design for a hairdresser platform, as shown and described.

DESCRIPTION

FIG. 1 is a perspective top front right view of a hairdresser platform, showing our new design;

FIG. 2 is a perspective top rear left view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines in the figures are for the purpose of illustrating portions of the hairdresser platform, which form no part of the claimed design.
